UNITED STATES PATENT OFFICE.

STEFAN NIKEL AND THOMAS LISTOSKI, OF NEW YORK, N. Y.

RAILROAD SIGNAL DEVICE.

1,322,130.

Specification of Letters Patent.

Patented Nov. 18, 1919.

Application filed August 2, 1919. Serial No. 314,953.

To all whom it may concern:

Be it known that we, STEFAN NIKEL, a citizen of Poland, residing at New York, county of New York, and State of New York, and THOMAS LISTOSKI, a citizen of Poland, residing at New York, county of New York, and State of New York, have invented certain new and useful Improvements in Railroad Signal Devices, of which the following is a specification.

This invention has as its object the provision of track-side devices whereby danger or like signals may be displayed in advance of an approaching train in such manner as to warn the operator of the impending danger of collision.

A further object is to provide track-side devices which are automatically operated by the passing train and without effort of the operator.

These and other like objects, which will become more fully apparent as the description progresses, are attained by the novel construction and combination of parts hereinafter described, and shown in the accompanying drawings, forming a material part of this disclosure, and in which—

Figure 1 is a plan view showing a rail track section having a branch crossing over another track parallel with the first, and indicating the application of the invention.

Fig. 2 is an enlarged fragmentary plan view taken in the vicinity of the numeral 2 on Fig. 1.

Fig. 3 is a transverse sectional view taken on line 3—3 of Fig. 2.

Fig. 4 is an enlarged longitudinal sectional view taken through a pair of the track-side devices.

Fig. 5 is a top plan view of the same, the covers being removed, and

Fig. 6 is a vertical sectional view taken on line 6—6 of Fig. 4.

Referring to the drawings in detail, the numeral 15 indicates a conventional type of straight or through track having a branch 16, the same crossing another track 17 at an oblique angle.

Mounted adjacent to one of the track rails on each track, in advance of the crossing, or branch, are relatively narrow, rectangular metallic casings 18, from which project plungers 19, while upon the opposite side of the curve, are similar but smaller casings 20, having extending plunger heads 21.

Extending below the plunger heads 21 are

vertical stems 22, slidably engaged with brackets 23, and pivotally connected at their lower ends by pins 24 with the horizontal arms 25, of bell-crank levers, pivoted on spindles 26 passing transversely through the casings 20, the vertical arms 27 of the bell-crank levers being pivoted to rods 28, which extend closely adjacent to the track rails to the casings 18.

These rods engage the arms 29 of bell-crank levers, pivoted on spindles 30 passing transversely through the casings, the other arms 31 of the bell-crank levers being forked and containing slots 32 engaging pins 33 set in the levers 34, pivoted on spindles 35, carried in insulating elements 36 and 37 secured to the inner surfaces of the casing walls. The levers 34 are normally held in raised position, due to coiled compression springs 38, extending from the bottom of the casings upward to the levers, which levers have formed upon their upper sides detents 39, the purpose of which will be further on described.

Extending downward through insulating elements 40, are stems 41 formed with the plunger heads 19, these stems being rigid with angularly disposed levers 42, fulcrumed on spindles 43, held by insulating elements 44 and 45 to the walls of the casing 18, while extending downward from the opposite sides of the axes 43, from the levers 42 are arms 46, normally drawn toward the end of the box by coiled tension springs 47, the ends of the arms normally resting upon the detent portions 39 of the levers 34, and which may be engaged thereby when the plungers 19 are depressed, permitting the detents to rise and engage with the lever 95 ends of the arms.

Engaged with the spindles 43 are electric conductors 48, leading from one pole of the batteries 49, the other pole of the batteries being similarly connected with electric conductors 50, engaged with brackets 51, secured to insulating elements 37, these brackets having inwardly extending arms 52, contactable with similar arms 53, slidably engaged with the lever arms 46, and pressed normally outward, due to the effect of bent flat springs 54, the arrangements being such that when the flanges of the wheels of a passing train make contact with the plunger 19 as to depress the same, causing electrical contact between the conductors 48 and 50, the same remains in contact, due to the arm

46, being held by the detent 39, until the train is further advanced and the wheels make contact with the plunger 21, operating the bell-crank levers connected therebetween 5 to depress the detents 39, thereupon the springs 47 raise the plungers 19 into position for further operation.

When the contacts 52 and 53 are in engagement, a circuit is formed through wires 10 48 and 50, energizing the electric lighting signals 55, visibly announcing that the train is approaching a dangerous location.

At the intersection of the curved track and straight track, indicated by the numeral 15 2, the connecting rods 28 are engaged by a pin 56 with a slot 57 in the lever 58, fulcrumed at 59, and also connected by the pin 56 is the outer end of a diagonally disposed lever 28, so as to transmit rectilinear movement 20 throughout the linked connection in a smooth and easy manner.

From the foregoing it will be seen that an effective signal operating device has been disclosed, which is automatically operated 25 by the passing of the train, the signals showing clearly whether or not the adjacent track sections are free to move upon or if a train is approaching thereon.

Having thus described my invention what 30 I claim as new and desire to secure by Letters Patent, is—

1. In a railway signal device, the combination with track side devices consisting of make and break elements, casings therefor, a 35 source of electrical energy, and connections between said source of electrical energy and one of said contact elements, of a plunger extending above one of said casings, said plunger being insulated from the walls thereof

and engaged with one of said electric elements, a fixed arm in said casing engaged with the other of said electric elements, a detent lever pivoted in said casing engageable with said arm whereby said elements are held when in engagement, fixed connections extending from said detent lever to the other of said casings, a plunger mounted in the other casing, and linked connections therebetween whereby said detent lever is released upon the passing of a train over the plunger 50 in said second casing.

2. In a railway signal device, the combination with a plurality of tracks, a source of electrical energy, signals in circuit therewith, and a trackside casing, of a plunger 55 movable in said track-side casing, an arm therein, a conductor from said source of electrical energy communicating with said arm, a fixed bracket in said casing, a conductor from the opposite pole of said source of 60 electrical energy connected with said fixed bracket, spring contacts carried by said arm adapted to engage said fixed bracket, a detent lever pivoted in said casing, means for normally pressing said detent lever upward 65 so as to cause engagement with said arm, a bell-crank pivoted in said casing, a second casing remote from the first, a plunger therein, a bell-crank lever engaged with said plunger at one end, and an operative connection with said levers whereby said arm is released simultaneously upon depressing said second plunger.

In testimony whereof we have affixed our signatures.

STEFAN NIKEL
THOMAS LISTOSKI.
